DIE STRUCTURE FOR METALLIC
CARTRIDGE BELT LINKS

Fred Goldfisher, Chicago, Ill., assignor to the
United States of America as represented by the
Secretary of War

Application March 24, 1944, Serial No. 527,974

4 Claims. (Cl. 59—6)

1

The present application constitutes a continuation-in-part of my application for United States Letters Patent, Serial Number 480,287, filed March 24, 1943, for "Die Structure for Metallic Cartridge Belt Links," which application has been abandoned in favor of this present application.

My invention relates to metallic belt links such as the type disclosed in Laystrom et al. Patent No. 2,286,286, dated June 16, 1942. In my copending application Serial No. 477,530, filed March 1, 1943, now Patent No. 2,426,448 dated Aug. 26, 1947, I disclose a link of this type to which I have added improved means for anchoring the ends of loops, particularly the hinge loop, to the link body so as to prevent opening of the loops or pulling away of the ends thereof from the link body when the link is subjected to longitudinal tension during service in a belt.

In the link disclosed in my copending application referred to, the means for anchoring a loop end to the link body comprises a headed member on the body and a slot in the loop end for receiving the headed member, together with a tie portion on the loop end spanning the neck of the headed member to hold the headed member intimately in the loop slot.

A purpose and object of my present invention is to provide cooperating die members which, during the final bending of the embryo link tongues into link loops, will effect the interconnection of the headed member and slot elements for anchoring loop ends to the body.

Another object of this invention is to provide in the formation of a belt link of the general type described a novel process for effecting the interlocking of the free end of the hinge loop with the body portion.

Several die structures have been designed for forming links of the type referred to, as, for example, die structure disclosed in the pending application of Fernlund et al. Serial No. 445,996, filed June 5, 1942 (Patent No. 2,355,964, issued August 15, 1944), and with slight alterations and additions to such die structure, my improved links can be efficiently and economically manufactured. On the accompanying drawings I have shown my invention applied to such die structures in which arbors operating between a die element and a punch element received embryo links with the anchorage or interlocking elements thereon, and in cooperation with the die and punch elements bend the tongues of the embryo links into final circular or loop form and coincidentally interengage the interlocking ele-

ments for anchoring loop ends to the link body. Referring to the drawings:

Figure 1 is a plan view of the end of a stock band showing the formation of the embryo links with the interlocking elements thereon;

Figure 2 is a plan view of an embryo link which has been severed from the stock band and which is to be subjected to die operation for bending of the tongues into loops and at the same time interlocking the interlocking elements;

Figure 3 is a side elevation of the embryo link after partial bending of its tongue toward circular or loop form;

Figure 4 is a side view of a finished link;

Figure 5 is a plan view of a finished link;

Figure 6 shows the link just before the end of a loop is brought into interlocking engagement with the link body;

Figure 7 is an end elevation of the die, punch and arbor elements which receive the embryo links;

Figure 8 is a front elevation of the parts shown in Figure 7;

Figure 9 is a front elevation showing, by dotted lines, the punch element displaced from the arbor element and, by full lines, engagement of the punch element with the arbor element for partial bending of the embryo link tongues;

Figure 10 is a front elevation of the die element which receives the partially bent tongues for final bending thereof into loop form and engagement of the interlocking elements when the punch and arbor elements shown on Figure 9 are moved downwardly;

Figure 11 is a lower end view of the punch and arbor elements with a completed link thereon;

Figure 12 is a lower end view of the punch element;

Figure 13 is a section on plane XIII—XIII of Figure 16;

Figure 14 is a section on plane XIV—XIV of Figure 16;

Figure 15 is a plan view of the die element;

Figure 16 is a section on plane XVI—XVI of Figure 7; showing the punch and die elements in engagement;

Figure 17 is a section on plane XVI—XVI of Figure 7 showing the punch element in connection with the arbor element for holding of an embryo link thereon and for partial bending of the link tongues towards circular form;

Figure 18 is a section on plane XVI—XVI of Figure 7 of the die element;

Figure 19 is a side view of the lower end of

the embryo link holding and interlocking bar;

Figure 20 is an enlarged perspective view of the interlocking elements of the link just before they are brought into engagement;

Figure 21 is a similar view of the same elements after engagement; and,

Figure 22 is an enlarged partial section taken on the same plane as Figure 16, illustrating the manner in which the shoe cooperates to bring the interlocking elements into engagement.

The link shown on Figures 4 and 5 is the improved link of my copending application referred to hereinbefore, the link comprising a body part 10 from whose ends at one side thereof extend the cartridge receiving loops 11 and 12, and from whose other side extends the hinge loop 13, the end of the hinge loop having the slot 14 (Figure 6) for receiving the extension 15 on the link body terminating in a head 16, the tie portion 17 at the end of the loop being deflected around the extension behind its head during the final bending of the loop into circular form.

By a slight modification of die elements such as disclosed in the Fernlund et al. application hereinbefore referred to, the slot 14 and the extension 15 may be readily formed in the stock band during progressive formation of the embryo link, as shown on Figure 1, Figure 2 showing a finished embryo link whose tongues are to be bent to final circular or loop form for engagement of the slot 14 and extension 15 for locking or anchoring of the loop end to the link body.

Figures 7 to 19 show substantially the die structure of the Fernlund et al. application referred to for performing the bending of the embryo link tongues into loops, but with modification and addition for adapting such die structure for also affecting the interengagement of the interlocking elements on the link. The punch element P is supported on the punch block 18 and the die element D is mounted on the die block 19 as best shown on Figure 16. The forming arbors 20 and 21 extend from a supporting block 22 which is vertically movable downwardly on posts 23 against the resistance of springs means (not shown) but disclosed in the Fernlund et al. application hereinbefore referred to.

As shown on Figures 1, 2, and 3, while the embryo link is being formed, the link body and the adjacent inner ends of the tongues for the loops 11 and 12 are deflected downwardly to form a V bend 24 which presents the transverse channel 25. As shown on Figures 9 and 10, when the punch member P is in its upper position indicated by the dotted line on Figure 9, the embryo link is fed in over the arbors with the V bend extending down between the arbors and the tongues of the link extending laterally outwardly as indicated by dotted lines in Figure 9.

Referring to Figures 12, 16, and 17, the punch element P has the forming surfaces 26, 27, and 28, the surfaces 26 and 27 cooperating with the arbor 20 and the surface 28 with the arbor 21. Extending through the punch element from between the surfaces 26, 27, and surface 28, is the guideway 29 for the holding bar 30, the bar terminating in a cup-shaped head 31 movable in the recess 32, a spring 33 between the head and the punch block 18 tending to hold the bar 30 shifted outwardly, as shown in dotted lines in Figure 9. The bar has the tapered or V-shaped end 34 for fitting into the channel 25 of the embryo link supported on the arbors, as shown on Figure 17. When the punch block with the punch element P is moved downwardly from the dotted

position shown in Figure 9, the bar 30 is held out by the spring 33 until its beveled end engages in the embryo link channel 25, and then as the punch member continues its downward movement the spring pressure will hold the bar against the link to keep it accurately seated on the arbors preparatory to engagement of the surfaces 26, 27, and 28 on the punch element with the link.

In its lower end, the bar 30 has a rectangular slot 35 in which is located the locking shoe 36 which effects the interlock between the slot 14 and the extension 15 on the link. This shoe is of a width to engage through the space between the cartridge receiving loops 11 and 12 of the link and is fulcrumed on a pin 37 extending through the bar. As shown on Figures 16 and 17, the shoe is of a thickness sufficiently less than the width of the guideway 29 so that the shoe may rock a distance on its supporting pin. The shoe terminates a distance below the end of the bar 30 and is tapered to follow substantially the taper 34 at the bar end. On its rear side, the end of the shoe has the inclined or wedging surface 38, and on its opposite side, in front of the wedge surface, the shoe has the recess 39 for receiving the tie portion 17 which spans the end of the slot 14 in the end of the loop which is to be anchored to the link body.

Referring to Figures 10, 15, 16, and 18, the die element D has the forming faces 40 and 41, and 42, the faces 40 and 41 receiving the loop tongues 11 and 12 and the surface 42 receiving the hinge tongue 13 when the punch element P together with the arbor block is moved downwardly with the punch block 18, these tongues being then bent around the respective arbors to form the finished link. Between the die faces 40 and 41 the die member D has the inclined or wedging surface 43 which is engaged by the wedging surface 38 on the locking shoe during the final engagement of the punch member P and die member D. Referring to Figure 17, when the punch member P is moved down to receive the arbors, the tapered end of the bar 30 engages in the link channel 25 at the bases of the loop tongues 11 and 12, and the projecting ends of the shoe 36 come alongside of the extension 15 on the link body with its recess 39 in alignment with the extension behind its head 16. As the punch member and the arbor block now move downwardly (Figures 17 and 18) the link tongues, which were partially bent down around the arbors by the punch member, will encounter the surfaces 40, 41, and 42 of the die member D and the tongues will be deflected around the arbors. Just before the wedge surface 38 at the end of the locking shoe 36 engages with the wedging surface 43 on the die member D, the end of the hinge loop tongue 13 will have been deflected around the arbor 21 for reception in the tongue slot 14 of the extension 15, and then, during the final movement of the punch element and arbors into engagement with the die member D, the wedge surface 38 on the shoe will engage the wedge surface 43 on the die member for rocking of the shoe to force its end portions 44 at opposite sides of the recess 39 into engagement with the ends of the tie portion 17 at the end of the loop to force the ends of the tie portion around and against the side edges of the extension 15 behind its head 16, to effect the interlock between the loop end and the link body, this final movement of the die structure and the shoe being shown on Figures 13, 16 and 22.

Referring to Figures 15, 16, and 18, a spreader 45 backed by a spring 46, extends through the die member D between the die faces 48 and 49 to engage between the loop tongues 11 and 12 of the embryo link to provide the proper distance between the tongues as they are bent to form the loops.

I have thus provided simple means on die structure for effecting interlock of a loop end with the link body during the final forming of the link loops. I do not desire to be limited to the exact means shown as changes and modifications are possible without departing from the scope of the invention.

It is, of course, inconsequential whether the headed extension or the cutout be formed on the body. Also it is clear that my invention may be employed in whole or in part in conjunction with other link forming mechanisms in addition to the one herein shown for illustrative purposes.

While the general construction disclosed comprises a very satisfactory means for effecting the interlocking of the body and the free end or ends of a loop forming tongue or tongues, it is, of course, evident that it is only one of a plurality of means which may possibly be employed in executing my novel process for interlocking a loop end with a link body. My said process which may also be carried out manually, for example, comprises in its preferred form the formation of the tie element 17 into a crowned or dome shape 17a. The direction of the crown is such that a recess is provided on the inner face of said tie and is preferably of dimensions such that said recess is capable of at least partially receiving the head portion 16 of the extension 15 so that said head may be thrust into registration with the cutout 14 through a path which passes said tie on the inner face side thereof and without those portions of the link which adjoin the ends of said tie being spaced from support or other structure a distance equal to the full thickness of the material from which said head is formed. In practicing my unique process I normally form a cutout such as 14 having a tie portion such as 17 on either the body portion of the link or on the general free end portion of a loop forming tongue and an extension such as 15 having a head such as 16 on the other of said link portions. Either simultaneously with the formation of the cutout or at some other time, I provide the tie 17 with a crowned contour 17a as heretofore mentioned. I then cause the said tongue end and said body portion to approach one another generally edge to edge and continue their relative motion to cause the head of the extension to pass, at least in part, through the recess provided by the crowning of said tie, into registration with the cutout. Thereafter, with said head received in said cutout I proceed to mold at least some of those portions of the tie which are not coextensive with portions of the extension proper into position behind said head whereby substantial movement of said head in one direction will cause engagement of portions of the edges thereof with edge portions of said tie. The exact shape of the head 16 is of course immaterial as concerns both my novel process and my forming apparatus and the effective or locking edge thereof may be disposed entirely on one side of the extension proper.

Although I have described specific embodiments of my invention for illustrative purposes, it is clear that modifications and eliminations which do not depart from the spirit and scope of my in-

vention will occur to those skilled in the art; therefore, I desire to be limited herein only by the appended claims.

I claim.

- 5 1. In a die structure for final forming of a finished link of the type disclosed, a pair of arbors adapted to support an embryo link provided with a single tongue extending laterally from one edge of a central body portion and a pair of tongues extending laterally from the other edge thereof, a punch member above said arbors, a die member below said arbors cooperable with said arbors to bend the tongues of the embryo link into loops and to bring a slot spanned over by a tie portion in said single tongue into position to receive a headed extension formed on said body portion, a shoe pivotally mounted on said punch member having a recess brought into alignment with said tie portion during the final movement of said punch member, and cooperating wedge surfaces on said shoe and said die member effective during the final movement of said punch member to force said shoe against the ends of said tie member 20 to intimately deflect said ends around the edges of said extension behind the head thereon whereby to lock the loop end to the body.
- 20 2. In a die structure for final forming of a finished link of the type disclosed, a pair of arbors adapted to support an embryo link having a body with a pair of tongues extending from one edge and a single tongue extending from the other edge, there being a slot spanned over the outer end of said single tongue by a tie portion 30 and a headed extension on said body for reception in said slot during final formation of said link, a punch member above said arbors and a die member below said arbors cooperable with the arbors upon downward movement of the punch member to bend the tongues into loops and to bring said slot into position to receive the extension on said body, a bar slideable in said punch member and a spring tending to shift said bar outwardly, said bar being tapered at its 40 outer end to engage in said embryo link channel under pressure of said spring to hold said embryo link on the anchors and having a slot in its outer end, a shoe in said slot engageable with the embryo link body adjacent to the extension thereon, said shoe having a recess for receiving the tie portion on said single tongue as said single tongue is bent into loop form around the corresponding arbor to bring the slot into position to receive said extension, and a wedging 45 surface on said die member engaging said shoe during the final movement of said punch member for forcing said shoe adjacent to its recess into engagement with the ends of said tie portion to intimately engage said ends around said extension behind the head thereon whereby to lock said single loop end to the link body.
- 45 3. Die structure for final forming of a finished link of the type disclosed, comprising a pair of arbors adapted to support an embryo link having a body with a pair of tongues extending from one edge and a single tongue extending from the other edge, there being a slot spanned over the outer end of said single tongue by a tie portion and a headed extension on said body for reception in said slot during final formation of said link, a punch member above said arbors and a die member below said arbors cooperable with the arbors upon downward movement of the punch member to bend the tongues into loops 55 and to bring said slot into position to receive

the extension on said body, a bar slidable in said punch member and a spring tending to shift said bar outwardly, said bar being tapered at its outer end to engage in said embryo link channel under pressure of said spring to hold said embryo link on the arbor and having a slot in its outer end, a shoe in said slot fulcrumed therein for swing at right angles to the axis of the arbors, said shoe having a recess for alignment with said tie portion after said single tongue has been bent around the corresponding arbor by said die member to bring its slot into engagement with said extension, and cooperating wedging surfaces on said shoe and said die member effective during the final movement of punch member to swing said shoe into engagement with said tie portion to deflect the tie portion ends intimately around the edges of said extension behind the head thereon whereby to lock the loop end to the body.

4. Die structure for final forming of a finished link of the type disclosed, comprising a pair of arbors adapted to support an embryo link having a body with a pair of tongues extending from one edge and a single tongue extending from the other edge, there being a slot spanned over the outer end of said single tongue by a tie portion and a headed extension on said body for reception in said slot during final formation of said link, a punch member above said arbors and a die member below said arbors cooperable with the arbors upon downward movement of the punch member to bend the tongues into loops and to bring said slot into position to receive the extension on said body, a bar slidable in said punch member and a spring tending to shift said bar outwardly, said bar being tapered at its outer

end to engage in said embryo link channel under pressure of said spring to hold said embryo link on the arbors and having a slot in its outer end, a shoe fulcrumed in said slot to terminate adjacent to said extension when said punch member receives said arbors, and cooperating wedge surfaces on said shoe and said die member effective during final movement of said punch member relative to said die member for causing said shoe to engage with the ends of said tie portion to deflect said ends intimately around the edge of said extension behind the head thereon whereby to lock the loop end to the link body.

FRED GOLDFISHER.
